Primary Examiner — Susan Bennett Hattan*Assistant Examiner* — Suzanne E Tisdell(57) **CLAIM**

The ornamental design for a radiator grille for an automobile, as shown and described.

DESCRIPTION

FIG. 1 is a front elevational view of a radiator grille for an automobile in accordance with our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a first side perspective view thereof;

FIG. 7 is a second side perspective view thereof;

FIG. 8 is an enlarged cross sectional view thereof along the lines 8 to 8; and,

FIG. 9 is an enlarged cross sectional view thereof along the lines 9 to 9.

The broken line showing of the radiator grille is for purpose of illustrating environmental structure and forms no part of the claimed design. The rear view of the radiator grille forms no part of the claimed design.
